SEAT STRUCTURE

Erving B. Morgan and James M. Ver Meulen,
Grand Rapids, Mich., assignors to American
Seating Company, Grand Rapids, Mich., a cor-
poration of New Jersey

Application July 10, 1936, Serial No. 89,865

1 Claim. (Cl. 155—82)

The present invention relates to seat structures and more particularly to chairs which are especially adapted for ready installation in base ball parks, grandstands and other outdoor sports arenas.

The primary objects of the instant invention are to provide a seat of the character above indicated which may be conveniently installed for use; to provide such a seat having means for 10 adjustably fitting the seat adjacent a vertical riser in installation; and, to provide such a seat which is utilitarian and comfortable in use, simple and rugged in construction and economical in manufacture.

15 An illustrative embodiment of the invention is shown in the accompanying drawing wherein:

Figure 1 is a fragmentary perspective view of the seat or chair;

Figure 2 is a fragmentary side elevational view 20 of the chair leg;

Figure 3 is a face view of one of a pair of chair leg supporting brackets; and

Figure 4 is a fragmentary side elevational view 25 of the manner in which the chair supporting member is secured to a vertical wall surface of a grandstand or the like and the manner in which the chair or seat is adjustably fitted to its supporting member.

Referring then to the drawing in which like 30 parts of the seat structure and its supporting means are designated by the same numerals in the several views, a chair adapted for installation in baseball parks, grandstands and the like has a folding seat 10 secured to hingedly connected seat supporting brackets 11 mounted upon the chair frame 12, here shown as of cast metal, and a back 13 is secured to the seat back supporting uprights 14 as by bolts 15.

The chair is preferably provided with a pair of 35 spaced depending legs 16 which are extensions of the seat back supporting uprights 14. Each leg has an upper longitudinally slotted portion 17 therein and a lower apertured portion 18. The inner face of each slotted portion is provided with 40 horizontally disposed serrations 19 which are in a vertically disposed series, all as best shown in Figure 1.

A pair of chair leg supporting brackets 20 are provided, here shown as of cast metal and adapted 45 to be secured adjacent a vertical riser 21 of concrete or the like, and in spaced horizontal position in the manner hereinafter set forth. These brackets 20 are each provided with an aperture 22 therein and the outer face of each aperture 50 is provided with horizontally disposed serrations

23 which are in vertically disposed series, all as best shown in Figure 3.

Means for securing each bracket 20 adjacent the vertical riser 21 in spaced horizontal position and for securing each leg 16 of the chair to a bracket 20 in vertically adjusted position comprise expansion bolts 24 projecting from the riser 21 and respectively extending through the aperture 22 of each bracket and through the slotted portion 17 of each leg and similar bolts 25 which 10 likewise project from the riser 21 and respectively extend through the aperture portion 18 of each leg. The ends of the expansion bolts 24 which extend through respective portions 17 and 22 in each chair leg 16 and the expansion bolts 25 are 15 threaded to receive the nuts by means of which the chair legs are respectively pressed into gripping contact with the bracket 20 and the riser 21 respectively.

The chairs are installed in the following manner: the desired height of the seats having been determined, the expansion bolts are accordingly inserted into the riser. In cases where it is desired that the seats be installed relatively high with reference to the riser, the upper bolts are 25 embedded near the top of the riser, and the lower bolts are so disposed that the upper bolts extend through near the bottom of the slots in portions 17. In cases where it is desired that the seats be installed relatively low, the lower bolts are em- 30 bedded near the bottom of the riser, and the upper bolts are so disposed that they extend through near the top of the slotted portions 17 to insure maximum bracing, but in cases where the risers are so low that this is impracticable, the 35 upper bolts are disposed lower.

The bracket 20 and the slotted portion 17 have serrated portions to insure a positive engagement therebetween. In cases wherein the bolts 24 extend through the slotted portions 17 at any point other than near the top of the slot, and in the absence of such positive engagement, the entire downward thrust of the chair leg depends on the lower bolt. In fact, this engagement between these serrated portions makes possible the entire 45 elimination of the lower bolts, though obviously the support is strengthened by their inclusion.

A further purpose of the slotted portion 17 is to allow compensation for incidental variations in the distance between each vertically aligned pair 50 of bolts.

While but one specific embodiment of this invention has been herein shown and described, it will be understood that certain details of the construction shown may be altered or omitted with- 55

out departing from the spirit of this invention as defined by the following claim.

We claim:

5 The combination with a vertical riser having an upper pair of horizontally spaced laterally projecting bolts and a lower pair of bolts respectively parallel to and in vertical alignment with the upper pair, each of the four bolts being screw threaded to receive a securing nut, and an aper-
10 tured serrated supporting bracket embracing the shank of each upper bolt, of a chair provided with

a pair of depending legs each having an upper serrated longitudinally slotted portion and a lower apertured portion respectively embracing an upper bolt shank and a lower bolt shank, each of said portions being retained in facing engagement with a supporting bracket and the vertical riser respectively by a nut in screw threaded engagement with each bolt shank. 5

ERVING B. MORGAN. 10
